UNITED STATES PATENT OFFICE.

JOHN MACON TORRENCE, OF DECATUR, GEORGIA.

TIMING DEVICE.

1,413,202.

Specification of Letters Patent. Patented Apr. 18, 1922.

Application filed May 25, 1920. Serial No. 384,059.

To all whom it may concern:

Be it known that I, JOHN M. TORRENCE, a citizen of the United States, residing at 117 McDonough Street, Decatur, in the county 5 of Dekalb and State of Georgia, have invented a new and useful Timing Device, of which the following is a specification.

This invention relates to a timing device whereby after the lapse of any predetermined period of time, an alarm will be sounded, one of the objects of the invention being to provide a simple, compact and efficient structure particularly designed for use in kitchens and by means of which several 15 predetermined periods of time can be set and an alarm will be sounded successively upon the completion of each of said periods, the operation of said structure serving automatically to return the set parts to their 20 normal positions after the signal has been operated.

With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention 30 shown can be made without departing from the spirit of the invention.

In the accompanying drawings the preferred form of the invention has been shown.

35 In said drawings—

Figure 1 is a front elevation of the structure.

Figure 2 is a section on line 2—2, Figure 1.

40 Figure 3 is a detail view of a portion of a modified form of mechanism.

Referring to the figures by characters of reference 1 designates the casing in which the clock mechanism indicated generally as 45 2 is mounted, the same being insulated from the casing in any suitable manner, as by means of blocks 3. The arbor 4 driven by the clock mechanism extends into the central portion of an opening 5 formed in one 50 face of the casing 1 and secured to this arbor and mounted for rotation in the opening is a disk 6 having an annular series of graduations at the margin thereof which can represent minutes or other periods of 55 time. Extending radially into the margin of the disk at each of the graduations there-

on, is a recess 7 having a longitudinal slot 8 extending through one face of the disk. In each of these recesses 7 is slidably mounted a bolt 9 having a shoulder 10 projecting from its inner face and a spring 11 connected to the bolt and to the inner end wall of the recess and serves to hold the bolt normally retracted into the recess. A stem 12 projects from each bolt and slides with- 60 in the slot 8, said stem having a head 13.

A circular series of graduations, indicated at 14, are provided on the apertured face of the casing 1 and extend around the opening 5, these graduations being adapted to 70 register with the graduations on the disk 6 and certain of said graduations 14 being designated by numerals as shown, thus to indicate series of time.

Arranged within the casing 1 is a bracket 75 15 preferably insulated from the casing and having a stem 16 on which is mounted a lifting roller 17. This roller is located adjacent the zero (0) graduation on the casing 1 and is electrically connected to a bell 80 18 or other signal, a battery 19 or other source of electrical energy, and to the clock mechanism 2.

It is to be understood that under ordinary 85 conditions all of the bolts 9 are retracted into their recesses 7 so that the disk 6 can thus rotate freely without causing the signal 18 to be operated. Should it be desired to have the signal operated after an interval of fifteen minutes, the operators press out- 90

wardly and inwardly upon the head 13 registering with the graduation 14 designated by the numeral 15 on casing 1. Thus the bolt 9 controlled by said head 13 will be shifted radially and inwardly so that 95 its shoulder 10 will engage the edge of the disk 6. This will hold the spring 11 under tension with the bolt 9 projecting beyond the periphery of the disk. After the completion of fifteen minutes this projecting 100 portion of the bolt 9 will be brought into position to ride on the roller 17. Thus it will be shifted so as to disengage the shoulder 10 from the disk 6 and allow the spring 11 to retract the bolt 9 into the 105 recess 7. As long as the bolt 9 is in contact with the roller 17 a circuit will be completed to the alarm 18 which will be sounded until the bolt has been retracted away from the roller 17. Obviously several 110 of these bolts may be projected at different distances from the zero graduation and they

will successively sound the alarm and be released. Thus the device can be employed for indicating several periods of time and is therefore particularly useful where it is desired to cook various articles for different periods.

While the structure is especially useful in kitchens, it is to be understood that it can be employed advantageously wherever a time signal is desired. Also it is to be understood that the disk 6 can be provided with any number of graduations and the casing 1 can also be provided with a corresponding number of graduations. For example instead of providing a disk which rotates once an hour a disk can be provided that will rotate in a shorter period or in a longer period. Furthermore any suitable means, not shown, may be provided for stopping the clock mechanism when it is not desired to use the device.

Instead of having the alarm operated electrically, mechanical means may be provided for this purpose. For example, and as shown in Figure 3, a clock mechanism can be provided in a separate casing 20, this mechanism including a wheel 21 having notches in the periphery thereof and any one of these notches is adapted normally to receive a holding finger 22. This finger extends from a rock arbor 23 from which extends a long arm 24 inclined upwardly into the path of the projecting bolt 9. A spring 25 can be employed for holding the finger 22 normally in engagement with the wheel 21 of the clock mechanism. A bell 26 is provided and is adapted, when the wheel 21 is released, to be sounded by ordinary clock mechanism such as used in alarm 40 clocks.

It will be apparent that when the disk or wheel 6 rotates, the projecting bolt 9 will come against the inclined arm 24 and gradually depress it, lifting the finger 22 against the action of spring 25 so as to release wheel 21 and cause the alarm 26 to be sounded. As the bolt 9 continues to move with the disk or wheel 6, it will continue to move the arm 24 downwardly until said arm

comes into contact with a stop 27 whereupon the bolt 9 during its further movement will be elevated by the restrained arm 24 and thus disengaged at its shoulder pin so that the spring 11 will pull the bolt back in the recess 7. As soon as the bolt 9 is thus disengaged from the arm 24, the spring 25 will return the finger 22 to engagement with the wheel 21 and stop the mechanism operating the alarm.

While the mechanical means for controlling the alarm can be carried by a separate casing, it is to be understood that, if desired, it can all be included within one casing indicated at 2 in Figure 2.

What is claimed is:

The combination with a casing having an opening therein and a series of graduations extending around the opening, of a disk mounted for rotation in the opening and constituting a closure therefor, there being an annular series of radial recesses extending into the periphery of the disk, bolts slidably mounted within the respective recesses, yielding means for holding the bolts normally retracted into the recesses, means extending through the top of the disk for shifting the bolts radially out of their normal position, a shoulder upon each bolt shiftable downwardly into engagement with the wall of the recess of the bolt to hold said bolt projected beyond the disk, a lifting cam within the casing and in the path of the projecting bolt, means for rotating the disk to shift a projecting bolt against the cam, said cam constituting means for lifting the bolt to disengage its shoulder and permit retraction of the bolt, and an alarm, said bolt when engaging the cam, constituting means for effecting the actuation of the alarm.

In testimony that I claim the foregoing as my own, I have hereto affixed my signature in the presence of two witnesses.

JOHN MACON TORRENCE.
